UNITED STATES PATENT OFFICE.

ROBERT L. PATE, OF SPRINGFIELD, MISSOURI.

RADIATOR SHELL FOR INTERNAL-COMBUSTION ENGINES.

Application filed February 5, 1925. Serial No. 6,931.

To all whom it may concern:

Be it known that I, ROBERT L. PATE, a citizen of the United States, residing at the city of Springfield, county of Greene, and 5 State of Missouri, have invented a new and useful Radiator Shell for Internal-Combustion Engines, of which the following is a specification.

This invention relates to radiator shells 10 for internal combustion engines.

An object of the invention is to provide an improved radiator shell adapted to be attached to a radiator core and provided with vertical guide channels for guiding and 15 retaining a number of shutter elements to protect and cover the radiator, and provided with means for holding the ends of the lower shutter or shutters between the shell and the radiator while the upper shutter or shutters 20 are permitted to move freely to different vertical adjustments without obstruction by the lower ones.

Another object of the invention is to provide an apparatus of the character mentioned in which provision is made whereby 25 all of the shutters may be mounted in position for use, or removed from the apparatus with facility and without detaching the radiator shell of which the guiding and retaining means is a part.

Another object of the invention is to provide a radiator shell having guiding and retaining channels for supporting a number of shutter elements so that they may be maintained in overlapping relationship in different 35 adjustments to afford proper protection to the radiator under different conditions and variations in temperature.

Another object of the invention is to provide a radiator shell having guiding and retaining channels constructed and designed to permit placement and removal of the shutter elements in proper overlapping relationship, and embodying the important structural subject matter herein disclosed.

Various other objects and advantages of the invention will appear from the following description, reference being made to the drawings in which—

Fig. 1 is a front end elevation of a radiator and shell containing the invention.

Fig. 2 is a vertical sectional view.

Fig. 3 is a perspective view showing one side of the radiator shell of preferred form.

Fig. 4 is a cross sectional view on the line 55 4—4 of Fig. 3.

Fig. 5 is a front end elevation of an alternative form of the invention.

Fig. 6 is an enlarged vertical longitudinal sectional view of the form of the invention shown in Fig. 5.

Fig. 7 is a front end elevation of an additional alternative form of the invention.

Fig. 8 is a cross sectional view of the invention shown in Fig. 7.

Fig. 9 is a front end elevation of an embodiment of the invention in which the channel structure is detachable from the shell.

Fig. 10 is a cross sectional view on the 70 line 10—10 of Fig. 9.

Fig. 11 is a perspective view of the channel device detached from the shell.

The radiator shell shown in Figs. 1 to 4 inclusive is in the form of a frame containing the radiator core, said frame having inwardly and downwardly extended portions 1 forming an opening through which the radiator is exposed. The inner side edge of each of the vertical portions 1 of the radiator shell is folded to provide a channel comprising inner walls 2 pressing against the parts 1 and outer walls 3 facing inwardly and spaced from the walls 2 as clearly shown in Figs. 3 and 4. The outer wall 3 of each channel is cut to provide a gap 4 intermediate of the upper and lower ends of the channel through which the ends of the shutter elements 5 may be passed in the insertion and removal of said elements.

The vertical portions 1 are spaced from the radiator core a distance sufficient to permit the ends of a shutter element 6 to extend between the shell and the radiator. For the insertion and withdrawal of the shutter element 6 a gap 7 is formed in the inner wall of each channel. This permits the shutter elements 6 to be inserted in the channels 2 through the gaps 4 and the ends of said shutter element to be passed through the gap 7 to positions between the channels 2 and the radiator core. Thus, the lower shutter element 6 is held closely against the radiator core behind the channels 2, while the upper shutter element is movable vertically 100 in front of the lower element 6 and in overlapping relationship thereto.

The lower portion 8 of the radiator shell

is somewhat rearwardly from the planes of the side portions 1 and forms a transverse ledge upon which the lower edge of the shutter element 6 is supported. The shutter element 6 may be held from lateral movement by the bead formations 9, or other equivalent structure designed and adapted to abut against the inner edges of the rear walls 2 of the channels, as will be understood by reference to Fig. 4.

The upper shutter element 5 may be raised and lowered from within the seating portion of the automobile by a flexible connection 10 extending from the upper edge of the element 5 into the seating portion of the automobile. As shown, the connection 10 passes through the lower edge of the upper horizontal portion 1 of the radiator shell and through the radiator core to the seating portion of the automobile. This arrangement may be varied as desired.

The front walls 3 of the channels are extended across the top so that when the shutter element 5 is in its uppermost adjustment the upper edge thereof is within a horizontal channel.

The gaps 4 may be closed by strips 11 utilizing appropriate fastening devices such as the ball and socket fasteners 12, or other suitable retaining means permitting easy attachment and detachment of said strips. The ball members 12 of these fasteners may constitute part of a series of fasteners, the others of which include similar parts 13 for engagement by cooperative members on the hood or radiator cover when it is desired to use the cover.

The alternative form of the invention shown in Figs. 5 and 6 is without the gaps 4 and comprises the gaps 7 to permit the lower shutter element to be passed to and from the channels. The channels comprising the rear walls 2 and the front walls 3 open at their lower ends to permit the shutter elements to be inserted therethrough and to pass therefrom. In assembling the shutter elements within the device the lower shutter element 6 is first passed upwardly into the channels and upwardly through the gaps 7 until its ends are between the radiator shell and the radiator core; and then the shutter element 6 is moved downwardly to the supporting ledge 8. Next the ends of the upper shutter element 5 are passed into the channels and guided to and retained in proper position by the connection 10.

The alternative form of the invention shown in Figs. 7 and 8 omits the gaps 4 and 60 the gaps 7, but is otherwise the same as the form of the invention shown in Figs. 5 and 6. The upper shutter element may be inserted and withdrawn through the lower ends of the channels, while the lower shutter element may be flexed, as indicated in Fig.

8, sufficiently to insert its ends between the radiator shell and the radiator core, or to withdraw them therefrom. In other particulars the structure of the radiator shell is the same as that previously described.

The form of the invention shown in Figs. 9 to 11 comprises separate channel structure including a strip of metal shaped to form vertical side channels and a transverse channel at the top. The strip of metal is shaped to provide an external flange 14 arranged to engage between the radiator core and the vertical horizontal front portions 15 of the radiator shell. The strip of metal is further shaped to provide a front channel wall 16 for a rear channel and a front channel wall 17 for a front channel, the same being designed and adapted to receive the ends of the lower and upper shutter elements 5 and 6, respectively. It is obvious that when the shutter elements are in place the channel device cannot become detached as the ends of the shutter elements constitute abutments preventing inward flexing of the side channel members. The lower ends of the side channel members rest upon supporting portions 18 of the radiator shell.

The corners or sections of union of the upper horizontal channel structure with the upper ends of the vertical channel members are rendered flexible by the formation of a number of notches 19 in the flange 14. A sufficient number of such notches are provided to permit the vertical channel members to be pressed toward each other so that the flanges 14 may be passed between the shell portions 15 and the radiator core, after which the vertical channel members are spread apart and the flexible shutter members are inserted. According to this form of the invention the device is in two parts comprising the radiator shell proper and the channel structure for holding the shutter elements in place.

The invention may be embodied in other forms and comprise additional variations without departure from the nature and principle thereof. I have not attempted to suggest or illustrate all of the forms and variations which the invention comprises as they will readily suggest themselves to those familiar with this class of inventions. I contemplate such variations as may be found useful or expedient in constructing or adapting the invention to uses for which it is intended.

What I claim and desire to secure by Letters Patent is:—

1. A radiator shell adapted to be attached to a radiator core and having its vertical front side portions spaced from the radiator core for the purpose described, and a vertical channel in connection with each of said vertical front side portions, the front and rear walls of each of said channels having

gaps therethrough intermediate their upper and lower ends.

2. A radiator shell adapted to be attached to a radiator core and having its vertical front side portions spaced from the radiator core for the purpose described, a vertical channel in connection with each of said vertical front side portions, the front and rear walls of each of said channels having gaps therethrough intermediate their upper and lower ends, and detachable elements for covering the gaps in the front walls of said channels.

3. The combination with a radiator core, of a radiator shell comprising vertical side front portions spaced from the radiator core and forming therewith intervening spaces for the ends of shutter elements, and a vertical channel in connection with each of said front portions of said shell arranged to receive the ends of shutter elements.

4. The combination with a radiator core

and a radiator shell in which the core is supported, of a pair of guide channels engaging between the shell and the core, and a cross portion having flexible connection with said channels respectively, which connections permit movement of said channels for engagement with and disengagement from the radiator shell and core as aforesaid.

5. The combination with a radiator core and a radiator shell in which the core is supported, of a pair of guide channels engaging between the shell and the core, a transverse portion having flexible connection with said channels respectively, which connections permit movement of said channels for engagement with and disengagement from the radiator shell and core as aforesaid, a flexible shutter element having its ends between said channels and the radiator core, and an additional flexible shutter element having its ends in said channels.

ROBERT L. PATE.
